UNITED STATES PATENT OFFICE.

JOSEPH SPILLINGER, OF LANCASTER, PENNSYLVANIA.

LAMP-SUPPORT.

SPECIFICATION forming part of Letters Patent No. 321,545, dated July 7, 1885.

Application filed January 19, 1884. (No model.)

To all whom it may concern:

Be it known that I, JOSEPH SPILLINGER, a citizen of the United States, residing at Lancaster, in the county of Lancaster and State of Pennsylvania, have invented certain new and useful Improvements in Lamp-Supports; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this specification.

15 This invention relates to lamp-brackets of the extensible kind; and it consists, partly, in certain devices for regulating the longitudinal adjustment of the horizontal arm, partly in certain devices for holding said arms to the 20 vertical part of the bracket and regulating its axial adjustment, and finally in the bracket as a whole, all substantially as hereinafter set forth.

25 In the accompanying drawings, Figure 1 represents an elevation of my improved bracket, the vertical standard being partly broken away to show the fastening-screw and the grooved shank into which it works. Fig. 2 represents a detail view of the outer section 30 of the horizontal bar, taken from the opposite side. Fig. 3 represents a detail perspective of the shanks from below.

35 A designates a vertical standard, preferably of cast metal, having a base, A', adapted to rest upon and be attached to a shelf or other suitable support. In the top of this standard there is a deep cylindrical socket, and the wall of this, a short distance above the bottom, is screw-tapped to receive a milled screw, B, the 40 operative part of which is long enough to extend some distance into said socket.

45 C designates the inner section of the horizontal lamp-holding arm, and C' the outer section thereof, these sections being, respectively, provided with registering longitudinal slots c c', and held together by screws, as hereinafter described. The inner section, C, is provided at its inner end with a hub, d, which is surmounted by an ornamental flat handle, d', whereby said bar may be turned on its axis from behind. This axis consists of a cylindrical shank, D, corresponding in length and

diameter to the socket in the top of standard A, and having formed in it a broad and deep annular groove, D', at such a height from its 55 lower end as to receive the end of screw B, aforesaid. The lower side of the groove is a broad shoulder, which, when the screw is turned fully home, will be in contact with said screw to such an extent as will effectually 60 prevent the said shank from being lifted in its socket. The lower end of said shank is rounded to form a convex bearing-surface, which turns with the least possible friction on the bottom of the socket. The shank, drum, 65 and handle, or ornamental top piece, aforesaid, are preferably cast in one piece with the inner section, C, of the arm. By loosening screw B, I leave the shank and arm free to turn to the right or the left, so as to present said 70 arm at any desired angle and hold the lamp where it may be needed. The screw B is then tightened again, and the lamp thereby secured in its new location. The lamp may, however, be still too near the person using it, or too far 75 from him, or it may be desirable, on other accounts, to shorten or extend the horizontal arm. To allow this I provide the sections CC' with the longitudinal slots c c', before alluded to, and make use of screws E F, the former of 80 which passes through slot c of section C and screws into section C', while the latter, on the opposite side, passes through slot c' of section C' and screws into section C. These screws are arranged, respectively, near the opposite 85 ends of their respective slots, and they serve as stops to limit the extension of the arm by engaging with the material at the outer end of slot c and the inner end of slot c', respectively. In like manner they prevent the 90 outer section, C', from being moved inward too far. They are the only means of attachment of said outer bar or section, and when they are unscrewed it falls away from the inner bar or section, C, or may be removed by 95 hand. These screws are loosened a little to allow the extension or contraction of said arm. This is effected by hand or in any convenient manner, and the screws E F are again tightened. In practice it will suffice to leave 100 one of said screws just loose enough to allow the section C' to slip over section C, and to use the other screw for the alternate loosening and tightening described. This latter screw is

preferably a thumb-screw, such as shown at 5 E in the drawings. The sections C C' are flat-sided, parallel, and of equal width, and the heads of the screws E F overlap the edges of the slots, so that it is not possible for the outer section, C', to turn (allowing the lamp to tilt on either side) without displacing or breaking said screws, and the construction of the bars or sections above stated lessens the danger of 10 that.

I am aware that it is not new to construct a 15 lamp-support with an extensible horizontal arm consisting of an inner tubular or deeply-socketed section, an outer section having a rod which enters such socket, and a screw which 20 works through the wall of said socket against the periphery of said rod; but it must be obvious that such a construction is much less reliable than mine for holding the lamp upright, 25 and much more likely to bend or break.

I am also aware that it is not new to use a 30 standard having a cylindrical socket with a horizontal separate arm having a cylindrical ungrooved rod or shank which turns therein, a screw working through the wall of said 35 socket against said rod or shank, and another screw working downward upon the top of the shank or rod, the former screw serving to allow 40 vertical adjustment and the latter to allow the radial adjustment of the arm. In such a 45 construction, however, there are two parts more than I use, the shank is held in the socket by friction only and not positively locked, and other details differ as stated.

I do not claim either of the above combinations of devices, nor both of them together. 50

It is obvious that my shank is capable of vertical adjustment in its socket by withdrawing screw B from its groove and afterward clamping it by screwing against the periphery 40 of said shank when the latter has been raised to the desired extent. Of course the groove may be at any part of said shank. My screw B is thus adapted to do duty either as a frictional clamping device or as a positive locking device. In 45 the former case it governs vertical adjustment as well as axial; in the latter it has nothing to do with vertical adjustment, except to prevent it, but secures the parts much more satisfactorily. 50

Having thus described my invention, what I claim as new, and desire to secure by Letters Patent, is—

The hub d, to which the extensible lamp-supporting arm is attached, and which is provided with the downwardly-extending stem D, having an annular groove, D', in combination with a hollow standard, A, which receives said stem and supports said hub, and a screw, B, which works through the wall of said standard and into the groove of said stem, substantially as set forth. 55

In testimony whereof I affix my signature in presence of two witnesses.

JOSEPH SPILLINGER.
